(57) **CLAIM**

The ornamental design for a bollard cap, as shown and described.

DESCRIPTION

FIG. 1 is an isometric view of a bollard.

FIG. 2 is another isometric view of the bollard of FIG. 1.

FIG. 3 is a side view of the bollard of FIG. 1.

FIG. 4 is another side view of the bollard of FIG. 1.

FIG. 5 is another side view of the bollard of FIG. 1.

FIG. 6 is another side view of the bollard of FIG. 1.

FIG. 7 is a top view of the bollard of FIG. 1.

FIG. 8 is a bottom view of the bollard of FIG. 1; and,

FIG. 9 is a magnification of a portion of the FIG. 1 isometric view.

The broken lines shown in FIGS. 1-6 and FIGS. 8-9 illustrate portions of the bollard cap that form no part of the claimed design.

1 Claim, 8 Drawing Sheets(56)
